UNITED STATES PATENT OFFICE.

WALLACE E. SARRAN, OF CINCINNATI, OHIO, ASSIGNOR TO THE CHARLES W. BRENE-
MAN COMPANY, OF CINCINNATI, OHIO, A CORPORATION OF OHIO.

SHADE ROLL.

Application filed January 29, 1927. Serial No. 164,623.

This invention relates to window shade rollers and is particularly directed to the mounting at one end of the roller for supporting that end of the roller and non-rotatably securing a spring carrying spindle within the shade roll. The conventional shade roller comprises an outer cloth winding reel and an inner spindle, said reel rotatably mounted at one end on a pivot bracket 5 secured to the window frame and at the other 10 cured to the window frame and at the other on the spindle. The spindle in turn is non-rotatably secured to a bracket on the window frame and extends well within the winding reel which serves as a support for that end of 15 the roller. The reel is spring actuated and its movements are governed by a mechanism at the spindle end of the roll, said mechanism described in United States Letters Patent No. 44,624. The present invention deals with the 20 construction of the attachment means for non-rotatably securing the spindle to the window frame.

Therefore an object of this invention is to provide a shank for non-rotatably mounting the spindle, said shank comprising a flat stamping, configurated similarly to an arrow tip, having a narrow elongated portion socketed into the end of the spindle and its outer end provided with a head, the shoulder 25 thereof preventing longitudinal displacement of a ratchet member which is a part of the reel controlling mechanism, the ratchet member non-rotatably held against the end of the spindle by the shoulder engagement and the 30 flat end of the spindle serving as the attachment portion adapted to be engaged in a window frame bracket.

Another object is to provide a shank for non-rotatably securing the end of a shade 35 reel spindle, said shank spacing the end of the shade reel away from the bracket in which the shank is mounted and preventing any injurious contact between the moving reel and the fixed bracket.

Another object is to provide a stamping 45 cut from flat plate adapted to be used as a shank piece for the stationary spindle of a window shade roller, said shank being cheaply manufactured, necessitating less 50 parts and being less apt to break due to its integral structure.

Other objects and certain advantages will be more fully set forth in the description of the accompanying drawings, forming a part 55 of this specification, in which:

Figure 1 is a sectional view taken longitudinally of the end of a shade roll assembly showing the improved mounting or shank securing the parts together and inserted in the end of the spindle.

Figure 2 is an end view of the shade roll illustrating the conventional means for governing the movement of the shade reel.

Figure 3 is a perspective view of the shank piece.

Figure 4 is a perspective view of the metal ferrule capping the end of the spindle.

Figure 5 is a perspective view of the stationary member or ratchet of the control mechanism for governing the shade roll 70 movement.

Figure 6 is a general view showing the shade roll in service on a window frame.

Referring to the drawings, the shade cloth winding reel is indicated at 1 and is shown as of tubular construction. A spindle 2 is shown mounted within the tubular reel member 1 at one end thereof for rotatably supporting that end of the reel. A cap 3 is placed over the end of the shade reel and has its inner end provided with a downwardly turned lip 4 imbedded in the wood of the shade reel. The outer end of the cap provides a flange 5 rigidly maintaining a pawl carrying member 6 against the end of the shade reel. A pair of pawls 7 are pivotally mounted to the base of the cup-shaped member 6 and are overhung by the flange 5 of the cap. These pawls 7 being carried by the reel, rotate about, and cooperate with a stationary ratchet member 8 secured at the end of the spindle. The pawl and ratchet mechanism form the means for governing the rotation of the reel on the spindle and are of a well known type.

The end of the spindle 2 carries a bearing cap or ferrule 9, the outer end of the ferrule being formed to provide a shoulder 10 adapted to engage in an aperture centrally of the cup member 6, this being the rotative bearing for the reel. The inner end of the cap is provided with clip portions 11 for securing the end of the coil spring 12 to the spindle. The spring 12 is coiled about the spindle and has its opposite end secured to the reel, being engaged through a plug 13 pinned within the reel. The inner end 14 of the spindle is socketed within the plug in the tubular reel and the opposite end of the shade roller from that described in detail 110

comprises merely a pivot member 15 imbedded in the end of the shade reel and rotatably mounted in a bracket 16 on the window frame.

5 A shank 17 is formed by stamping a piece from sheet material to provide an outline resembling an arrow tip. This flat shaped member 17 has a narrow elongated portion 18 extending through the rectangular bore of 10 the stationary ratchet member and through a similar bore in the end of the ferrule 9 and is embedded or socketed into the end of the spindle itself, which has been drilled to receive same in a driving-fit. The tip of the 15 portion 18 may be sharpened for easy insertion and the shank is further maintained against relative movement in the spindle by means of a pin 19. The outer end of the shank provides a head portion 20, and wings or 20 tangs 22 intermediate the shank and head, the inner shoulder of the wings abutting the face of the stationary ratchet member 8 and holding it against the bearing cap or ferrule 9 so as to prevent longitudinal displacement 25 of the ratchet member. The head 20 of the shank is the attachment portion of the shank or mounting for the spindle and is adapted to be rigidly secured in a bracket 21 on the window frame. The outer shoulders of the 30 tangs (see Fig. 1) are disposed slightly beyond the end of the shade roller, so that they engage the bracket 21 and suitably space the roll end away from the bracket thereby preventing scraping of the end of the roll in the 35 stationary bracket.

By this construction the shank serves to hold the ratchet member 8 in place and extends through the end of the bearing cap and also into the spindle, thereby preventing any relative movements of these parts, so as to 40 maintain them all in a stationary position when the head of the shank is secured to the window frame.

Having described my invention, I claim:

In a window shade roller, a cloth winding 45 reel adapted to be rotatably supported at one end, a spindle mounted in the other end, a spring, one end of which is attached to the reel and the other end to the spindle, adjacent to its outer end, a ferrule disposed over 50 the outer end of the spindle, said ferrule adapted to provide a non-rotative anchorage for the spring, pawl mechanism carried by the end of the reel, a cooperating ratchet disposed against the ferrule upon the outer end 55 of the spindle, and a shank piece, comprising, a flat stamping provided with a tapered end entering the spindle, flanged wings on said stamping bearing against the ratchet to hold the ratchet and the ferrule non-rotatively to the outer end of the spindle and an outer end adapted to be mounted in the roller supporting bracket, said outer end of lesser diameter than said flanged wings so that said 60 wings space the end of the window shade roll 65 from the bracket.

In witness whereof, I hereunto subscribe my name.

WALLACE E. SARRAN.
